(57) **CLAIM**

The ornamental design for an enclosure system for cooling server racks, as shown and described.

DESCRIPTION

FIG. 1 is a front perspective view of a double enclosure system for cooling server racks in accordance with the present design;

FIG. 2 is a rear perspective view thereof;

FIG. 3 is a front elevational view thereof;

FIG. 4 is a rear elevational view thereof;

FIG. 5 is right side elevational view thereof, the left side elevational view being a mirror image thereof;

FIG. 6 is a top plan view thereof;

FIG. 7 is a front perspective view of a single enclosure system for cooling server racks in accordance with the present design;

FIG. 8 is a rear perspective view thereof;

FIG. 9 is a front elevational view thereof;

FIG. 10 is a rear elevational view thereof;

FIG. 11 is right side elevational view thereof, the left side elevational view being a mirror image thereof; and,

FIG. 12 is a top plan view thereof.

The broken lines shown in the drawings illustrate portions of the enclosure system for cooling server racks that form no part of the claimed design.
